Pls. 626

Samuel D. Nose of Albany, N.Y.
Letters Patent, No. 626 Dated February 14th 1854.
Ante-Dated, Dec. 30, 1853

The schedule referred to in these Letters Patent and making part of the same

To all whom it may concern:

Be it known that Samuel D. Nose, of Albany, County of Albany and State of New York, have invented a new and ornamental design for a looking glass, and do hereby declare the following to be a full and exact description of the same, reference being had to the annexed drawings, affixed to, and making part of this Specification.

The design cannot be easily described in words, and the several plates which embrace the design are represented in the drawings in their proper relation and designated by letters as follows.

(The various doors shown in the drawings being attached to certain plates are considered as forming parts of the plates).

Letter B. represents the bottom.

T.	"	top
F.	"	front
S.	"	side
I.	"	leg

What I claim as my invention, and desire to secure by Letters Patent, is the combination of the several ornaments and mouldings as arranged together in the drawings, the whole forming an ornamental design for a looking glass.
